UNITED STATES PATENT OFFICE.

ARCHIBALD McCALLUM, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,905, dated June 4, 1872.

To all whom it may concern:

Specification describing a new and original Design for a Carpet, invented by ARCHIBALD McCALLUM, of Halifax, in the county of York, England.

The accompanying photograph fully illustrates my invention.

This invention relates to the new design for the borders and outlines of three figures used on a carpet or other fabric. The main largest figure is of oval form, of which one-quarter is shown in the photograph. Its outline is scalloped on the inner edge, and is decorated with semi-rosettes, and surrounded with scrolls, as

shown. The smallest figure, of which one-half is shown, is also oval, and is placed on a light field, whose alternate protuberances have trefoils at their ends. The outline of the third figure is made to project in the middle of its sides and ends, and provided with outer decoration, as shown.

I claim as my invention—

The design for a carpet, as shown.

ARCHIBALD McCALLUM.
